ELECTRIC FLOOR WASHERS

Brendan Gallagher, 76 Grove St., New Canaan, Conn.
Filed June 13, 1963, Ser. No. 287,690
8 Claims. (Cl. 15—99)

The present invention relates to floor washing machines and in particular to machines having a revolving belt rotating over a pair of spaced rollers.

In the past many devices have been provided for washing or scrubbing floors. Some have utilized rollers and tanks or spraying or other means for providing the cleaning fluid.

Providing a clean belt or clean fluid has been a problem of the past since belts of the past have usually recirculated through the fluids they wiped up.

Fluid application of the past has not been uniform. Fluid applied to belts was either recirculated, getting progressively dirtier or sprayed onto a floor in the cleaning area or dipped onto a belt which recirculated either the clean fluid picked up by the machine or recirculated dirty fluid of some form.

According to the present invention, a simple continuous roller floor cleaning machine is provided which utilizes the same belt for applying the cleaning fluids and detergents which effectively segregates the clean fluid from the dirty fluid.

The electric floor washer operates as follows. Hot water (or other cleaning fluids) is fed by gravity through a manually operated valve into a dispenser at the front of the machine which splashes the water evenly over the breadth of a continuous belt. Underneath the top spongy surface layer of the belt is a firm base of rubber which is uniformly perforated over its entire surface. The belt moves around two big rollers and between two small squeezer rollers.

The water is absorbed by the dry spongy layer of the belt and as the belt rotates it brings the wet spongy surface in contact with the floor. The water and dirt form a dirty liquid solution which is carried by the sponge surface up over the big rear roller and down to the small squeezer rollers. Here the sponge layer is greatly compressed and the dirty liquid solution accumulates before the squeezer rollers and the solution pours through the perforations in the firm rubber base of the belt and descends into a sump. From here it is pumped up to a container on top which can be manually removed for emptying the dirty solution. Power is obtained from an electric motor. A spur gear on the output shaft of the motor meshes with a similar spur gear which is on the end of the top squeezer roller shaft. This spur gear in turn meshes with an identical spur gear on the end of the bottom squeezer roller shaft. The two squeezer rollers impart motion to the belt. The two big rollers are free to rotate in their bearings.

The person operating the machine would have to restrain it manually to get a sliding instead of a rolling action in order to get a good cleaning effect.

Although such novel feature or features believed to be characteristic of the invention are pointed out in the claims, the invention and the manner in which it may be carried out, may be further understood by reference to the description following and the accompanying drawings.

FIGURE 1 shows a side elevation of the essential details of the electric floor washer. Parts of the three spur gears are shown cut away for clarity. The electric motor is represented by the triangular shape in the center of the drawing. On the right of the motor is a square which represents the pump which is operated by a cam on the output shaft of the motor.

FIGURE 2 shows a front elevation of the essential details of the cleaning fluid dispenser.

FIGURE 3 shows a section of the cleaning fluid dispenser at lines 3—3 of FIG. 2.

5 FIGURE 4 shows an alternate form for the cleaning fluid dispenser.

FIGURE 5 is a section of the large rear roller which shows the essential details of the roller and the continuous belt at lines 5—5 of FIG. 1.

10 FIGURE 6 is a transverse view partly in section showing a spring mounting for the bottom squeezer roller in another embodiment of the present invention, at lines 6—6 of FIG. 1.

15 Referring now to the figures in greater detail, where like reference numbers denote like parts in the various figures—

20 The container for the cleaning fluid (No. 1, FIG. 1) has baffles to prevent waves. The gently sloping bottom of the container leads to the outlet which is connected by tubing to a manually controlled valve (marked V in FIG. 1). The valve could have a cable control which would be operated at the handle of the machine. The outlet end of the valve is connected to the dispenser which is fully described later.

25 The water leaving the dispenser is distributed evenly over the breadth of the spongy surface of the continuous belt (No. 3, FIG. 1).

30 The belt moves around two large rollers (Nos. 4 and 5, FIG. 1) and between two small squeezer rollers (Nos. 6 and 7, FIG. 1). The squeezer rollers are the same length as the breadth of the spongy surface of the belt. Outside the breadth of the belt and on the end of each roller are two identical spur gears which are in mesh. (For clarity all spur gears are shown partly cut away.)

35 The electric motor which provides the power for the machine is shown with a triangular shape and is situated approximately in the center of the machine. At the end of the output shaft (No. 8, FIG. 1) of the motor is a spur gear which meshes with the spur gear at the end of the top squeezer roller. On the output shaft of the motor there is also a cam (No. 9, FIG. 1) which is in contact with a roller follower which operates a pump (No. 10, FIG. 1).

40 The squeezer rollers driven by the motor pull the continuous belt and cause it to rotate around the two large rollers which are free to turn in their bearings. The wet spongy surface of the belt is dragged across the floor to be cleaned (the operator must hold the machine to prevent pure rolling) and the fluid and the dirt form a dirty solution which is carried up on the continuous belt over the large rear roller (No. 5, FIG. 1) and towards the two squeezer rollers. As the belt passes through the squeezer rollers, the spongy surface is greatly compressed and the dirty fluid builds up and flows through the spongy

55 layer and through the numerous perforated holes in the firm rubber base of the belt. The fluid falls through another perforated surface (No. 11, FIG. 1) and descends into a sump (No. 12, FIG. 1) from where it is sucked by the intake of the pump and pumped up to the container (No. 13, FIG. 1) for the dirty fluid. This container can be removed by the operator for emptying.

60 One form of dispenser 2 is shown in FIGURES 1, 2 and 3. The water having passed through the flow control valve (V, FIG. 1) falls into the dispenser where it spreads out along the length of the dispenser behind a retainer which is shown with a triangular section. When the water rises behind the retainer, it can flow through the cylindrical holes in the retainer and then fall down and pass through the nipples which protrude from the bottom of the dispenser. The water then drops on the spongy surface of the continuous belt. For increased flows of

water, the level will build up behind the dispenser and the water will flow over the top of the retainer. The various features in the dispenser are designed to effect a fairly uniform discharge of water over the length of the dispenser even when the floor is not quite horizontal.

FIGURE 4 shows an alternative method of construction for the dispenser. A retainer of rectangular section separates the inlet from the outlet side of the dispenser. There is a series of rows of cylindrical holes through the retainer. The other features are the same.

A section of the continuous belt is shown in FIGURE 5. The top ridge (No. 15, FIG. 5) of the firm rubber base prevents the water from flowing over the side of the belt as it passes through the squeezer rollers. The squeezer rollers compress the spongy surface (No. 3, FIG. 5) below the level of these ridges so that the ridges also guide the belt under the top squeezer roller. The other bottom ridge (No. 16, FIG. 5) on the inner surface of the firm rubber base sits in a recess on each end of the large rollers and guides the belt around the large rollers. It also guides the belt over the bottom squeezer roller. This ridge is at a slight angle off the vertical.

The base of the sump is in contact with the firm rubber surface of the belt in order to keep the pressure between the floor and the spongy surface of the belt as uniform as possible over the entire contact area.

As shown in FIG. 6, within the purview of the present invention is the removeability of the bottom squeezer roller from a spring mounting for the convenience of belt placement. Such mounting also serves to prevent the formation of permanent depressions on the belt when it is not in use.

The motor as shown is enclosed and naturally is insulated against the working fluid causing any malfunctioning.

Scraper 17 in combination with the rear roller 5 may be provided for the removal of large objects on the belt.

The terms and expressions which are employed are used as terms of description, it is recognized, though that various modifications are possible within the scope of the invention claimed.

Having thus described certain forms of the invention in some detail, what is claimed is:

1. A floor washing machine comprising a continuous belt including a spongy outer surface, a firm rubber base, perforations in said base adapted to allow the passage of fluid; a first roller; a second roller; said first and second rollers adapted to rotatably receive said belt; a pair

of squeeze rollers; said squeeze rollers located between said first and second rollers within lines joining the outer ends of the vertical diameters of said first and second rollers; said squeeze rollers adapted to engage said belt in squeezing relationship and further adapted to rotate said belt; a sump located within the perimeter of said belt adjacent said squeeze rollers; a first tank mounted outside the perimeter of said belt adapted to contain a cleaning fluid, said tank opening upon said belt and having valve means adapted to control the flow of said fluid onto said belt; a second tank outside the perimeter of said belt; a pump adapted to pump used fluid from said sump into said second tank; and a motor adapted to actuate said squeeze rollers and said pump.

2. A floor washing machine as defined in claim 1 and further including a sump having a flat lower portion adapted to hold the belt flat against the floor.

3. A floor washing machine as defined in claim 1 and further including a strainer adapted to strain fluid entering said sump.

4. A floor washing machine as defined in claim 1 further including inter-engaging gears on at least one end of said squeeze rollers.

5. A floor washing machine as defined in claim 1 further including baffles within said first and second tanks.

6. A floor washing machine as defined in claim 1 further including a dispenser, said first tank opening into said dispenser wherein the valve means are adapted to control the flow of the fluid onto said dispenser.

7. A floor washing machine as defined in claim 6 having a dispenser, said dispenser having nipples adapted to drip said fluid evenly over said belt.

8. A floor washing machine as defined in claim 1 wherein in said bottom squeezer roller is removably mounted on a spring mounting.
